United States Patent Office

Des. 187,962

Patented May 17, 1960

187,962

CIGARETTE PACKAGE

Bernard J. Tamarin, Whitemarsh, Pa.

Application September 10, 1956, Serial No. 42,890

Term of patent 14 years

(Cl. D58—12.6)

Fig. 1.

Fig. 2.

Fig. 1 is a perspective view of a cigarette package showing my new design; and

Fig. 2 is a top plan view thereof.

The drawing is shaded to indicate contrasting colored areas.

The dominant feature of my design resides in the portions shown in full lines.

The claimed invention:

The ornamental design for a cigarette package, substantially as shown and described.
